Specification for Design.

Patented June 7, 1921.

Application filed January 17, 1921. Serial No. 438,026. Term of patent 3½ years.

To all whom it may concern:

Be it known that I, ALFRED D. CROSBY, a citizen of the United States, residing at Attleboro, in the county of Bristol and State of Massachusetts, have invented a certain new, original, and ornamental Design for a Collar-Holder, of which the following is a specification.

In the accompanying drawings which form a part of this specification—

Figures 1 and 2 are a front view and an edge view respectively of a collar holder embodying my design.

I claim:—

The ornamental design for a collar holder, as shown.

ALFRED D. CROSBY.
